UNITED STATES PATENT OFFICE.

WILLIAM H. McCREERY, OF SAVANNAH, GEORGIA.

COLLAPSIBLE BARREL.

1,144,218.

Specification of Letters Patent. Patented June 22, 1915.

Application filed June 20, 1914. Serial No. 846,323.

To all whom it may concern:

Be it known that I, WILLIAM H. McCREERY, a citizen of the United States, residing at Savannah, in the county of Chat-
5 ham and State of Georgia, have invented certain new and useful Improvements in Collapsible Barrels, of which the following is a specification.

My invention relates to improvements in
10 collapsible barrels.

An important object of the invention is to provide a barrel of the above mentioned character, formed of few and simple parts, which may be quickly and easily assembled,
15 and which when in their knocked down condition will occupy the least space for the purpose of shipment or storage.

A further object of the invention is to provide a barrel of the above mentioned character, which is simple in construction, inexpensive to manufacture, convenient in use, and highly sanitary.

A further object of the invention is to provide a barrel of the above mentioned character, which is adapted to hold liquids, without leaking.

Other objects and advantages of the invention will be apparent during the course of the following description.

30 In the accompanying drawings forming a part of this specification and in which like numerals are employed to designate like parts throughout the same, Figure 1 is a side elevation of a barrel embodying my invention, parts being shown in section and parts broken away, Fig. 2 is a horizontal sectional view taken on line 2—2 of Fig. 1, Fig. 3 is an enlarged detail horizontal section through one of the joints of the stave-
35 sections, and, Fig. 4 is a longitudinal sectional view taken on line 4—4 of Fig. 3.

In the drawings, wherein for the purpose of illustration is shown a preferred embodiment of the invention, the numeral 5 designates stave-sections, which may be formed of compressed paper, fiber, wood or the like. These stave-sections are suitably curved in longitudinal and transverse cross-section and are tapered toward their opposite ends.

50 Secured to one longitudinal edge of each stave-section 5 is a tongue 6, preferably formed of sheet metal bent longitudinally upon itself, forming a hollow resilient element. This tongue may be secured to the stave-section by pins, screws, or the like as shown at 7.

Secured to one longitudinal edge of each stave-section 5, as more clearly shown in Figs. 2 and 3, is a double walled socket element 8. This socket element is preferably formed of a section of sheet metal bent upon itself for providing spaced walls 9, having a groove or socket 10 therebetween. The inner side of the socket element is bent to form 60 triangularly arranged walls 11, as shown. The walls 9 are suitably resilient, to coöperate with the resilient tongue 6, for affording a close or water tight connection or union therewith. The triangular arrangement of the walls 11 prevents the same from being 65 readily crushed by the contents of the barrel and also covers openings in the tongue and groove elements, whereby the barrel is 70 water tight. As clearly shown in Fig. 3, the socket element is approximately W-shaped in horizontal cross-section. The tongue 6 carried by one stave-section is inserted within the groove or socket 10 of the socket element 8 carried by the adjacent stave-section, as clearly illustrated in Fig. 2. 75

Each socket element 8 is provided with preferably vertically arranged elongated openings or slots 12, which are in registration and are adapted to register with corresponding openings or slots 13 formed in the tongue 6 and corresponding openings or slots 14 formed in hoops 15, as shown. These sets of openings are formed at suitably spaced intervals upon the socket and tongue elements, there being any suitable 80 number of hoops 15.

Keys 16 are provided to detachably hold or lock the tongue within the socket. Each key comprises a shank 17, carrying at its inner end a transverse locking head 18 extending laterally therebeyond for a substantial distance, as shown. The outer end of the shank 17 carries a turning head 19. It is obvious that by arranging the inner locking head 18 vertically, the same may be passed through the vertically arranged registering slots 12, 13 and 14, and by turning the key to bring the locking head to a horizontal position, such key will be securely held in place. The turning head 19 is arranged exteriorly of the socket 8 while the locking head 18 is within the same, as shown. 95

The upper and lower ends of the barrel are closed by removable heads 20, carried by annular flanges or rings 21, which are identical in all substantial respects with the hoop 15. The same keys 16 and associated 100 105 110

- elements are employed to detachably secure the rings 21 to the body portion of the barrel. The keys 16 holding the heads 20 in place, are arranged exteriorly of the heads.
5. From the foregoing it is obvious that I have provided a barrel formed of few and simple parts, which may be conveniently and quickly assembled and knocked down, and when assembled will be water tight.
10. It is to be understood that the form of my invention herewith shown and described is to be taken as a preferred example of the same, and that various changes in the shape, size, and arrangement of parts may be resorted to without departing from the spirit of the invention or the scope of the subjoined claims.
- Having described the invention, I claim:—
1. A barrel of the character described, comprising a plurality of stave-sections provided with double walled interfitting tongue and groove elements having apertures adapted for registration, and a member adapted to be inserted from the exterior of the barrel 25 through the apertures with its inner end arranged within the interior of the double walled groove element.
  2. A barrel of the character described, comprising a plurality of stave-sections provided with resilient double walled interfitting tongue and socket elements, and means to retain the tongue elements within the socket elements, substantially as described.
  3. A barrel of the character described, comprising a plurality of stave-sections, a tongue element secured to one longitudinal edge of each stave-section and provided with transverse openings, a double walled socket element secured to the opposite longitudinal 40 edge of each stave-section and having a groove to receive the tongue element and provided with transverse openings adapted for registration with the first named transverse openings, and a key provided with a 45 lateral extension to be inserted through the registering transverse openings and to be turned and held therein.
  4. A barrel of the character described, comprising a plurality of stave-sections, a
- socket element secured to one longitudinal 50 edge of each stave-section and formed of a section of sheet metal bent longitudinally for forming a double walled construction having an inner groove with its walls arranged within and spaced from the inner 55 and outer walls of said construction, the outer wall of said construction and the walls of the groove being provided with elongated openings which are in registration, a tongue element secured to the opposite longitudinal 60 edge of each stave and adapted for insertion within the groove and having elongated openings to register with the first named elongated openings, and keys for insertion through the registering elongated openings 65 provided at their outer ends with turning heads and at their inner ends with locking heads.
5. A barrel of the character described, comprising a plurality of stave-sections provided with interfitting tongue and socket elements having apertures adapted for registration, keys passed through the apertures to secure the tongue and socket elements together, and means arranged within the barrel to cover the inner ends of the keys, whereby the barrel is substantially water tight, substantially as described.
6. A barrel of the character described, comprising a plurality of stave-sections provided with interfitting tongue and socket elements having apertures adapted for registration, hoops surrounding the assembled stave-sections and provided with apertures adapted for registration with the first named 85 apertures, elements adapted to be passed through the apertures from the exterior of the barrel, and elements arranged within the barrel to cover the inner ends of the first named elements, whereby the barrel is substantially water tight, substantially as described.
- In testimony whereof I affix my signature in presence of two witnesses.
- WILLIAM H. McCRARY.
- Witnesses:
- W. H. CARTER,
H. P. COBB.
